PHOTOGRAPHIC CAMERA

Tsunezo Shimoda, Ohiko Yagi, Kinya Sawada, Takehiko Nakanishi, Sadao Okada, Hideki Ishii, and Masayuki Sakuma, Tokyo, Japan, assignors to Kabushiki Kaisha Ricoh, Tokyo, Japan

Filed Apr. 19, 1967, Ser. No. 6,755

Claims priority, application Japan Nov. 1, 1966

Term of patent 14 years

(Cl. D61—1)

FIG. 1

FIG. 2

FIG. 1 is a front, top and right side perspective view of a photographic camera, showing our new design;

FIG. 2 is a rear, top and left side perspective view; and

FIG. 3 is a right side elevational view thereof, with the front drum portion opened.

The bottom, not shown, is a substantially flat, unornamented surface.

Portions of the figures of the drawings are diagonally lined to indicate transparency.

We claim:

The ornamental design for a photographic camera, substantially as shown and described.
